CLAIM

The ornamental design for a combined set of containers and wall mounted hanging unit therefor, as shown and described.

DESCRIPTION

FIG 1 is a front perspective view of a combined set of containers and wall mounted hanging unit;

FIG. 2 is a rear perspective view of FIG. 1;

FIG. 3 is a front perspective view of one of the containers shown in open condition and shown separately for clarity of illustration only;

FIG. 4 is a rear perspective view thereof as shown in FIG. 3;

FIG 5 is a front perspective view thereof shown in closed condition;

FIG. 6 is a rear perspective view thereof as shown in FIG. 5;

FIG. 7 is a front perspective view of the wall mounted hanging unit shown separately for clarity of illustration only; and

FIG. 8 is a rear perspective view of FIG. 7.

Fig. 1*Fig. 2**Fig. 3**Fig. 4**Fig. 5**Fig. 6*Fig. 7

Fig. 8
